UNITED STATES PATENT OFFICE

105,059

DESIGN FOR AN EMULSIFIER

Oscar F. Neitzke, Belmont, Mass., assignor to Bennett Incorporated, Cambridge, Mass., a corporation of Massachusetts

Application May 1, 1937, Serial No. 69,103

Term of patent 14 years

To all whom it may concern:

Be it known that I, Oscar F. Neitzke, a citizen of the United States, residing at Belmont, in the county of Middlesex and State of Massachusetts, have invented a new, original, and ornamental Design for an Emulsifier, of which the following is a specification, reference being had to the accompanying drawing, forming part thereof.

Figure 1 is a front elevational view of an emul-sifier showing my new design;

Figure 2 is a rear elevational view; and Figure 3 is a top plan view of same.

I claim:

The ornamental design for an emulsifier substantially as shown.

OSCAR F. NEITZKE.
